MIDRIFF TOP OR SIMILAR ARTICLE

Marie M. Ryan, 12731 Moorpark, Studio City, Calif.

Filed June 29, 1964, Ser. No. 80,620

Term of patent 14 years

(Cl. D3—25)

FIG. 1.

FIG. 2.

FIG. 3.

FIG. 4.

FIG. 2 is a rear perspective view thereof;

FIG. 3 is a top plan view of the midriff top shown in FIG. 1 as it appears untied and laid out flat; and

FIG. 4 is a sectional view taken along the offset plane corresponding to line 4—4 of FIG. 3.

I claim:

The ornamental design for a midriff top or similar article, substantially as shown and described.
